UNITED STATES PATENT OFFICE.

WALTER P. MURPHY, OF CHICAGO, ILLINOIS.

METAL CAR-ROOF.

1,133,495.

Specification of Letters Patent. Patented Mar. 30, 1915.

Application filed June 25, 1914. Serial No. 847,186.

To all whom it may concern:

Be it known that I, WALTER P. MURPHY, a citizen of the United States, and a resident of the city of Chicago, in the county of Cook and State of Illinois, have invented a new and useful Improvement in Metal Car-Roofs, of which the following is a specification.

This invention relates to freight car construction, and consists in an improved metal roof composed of heavy gage roof plates and pressed sheet metal carlines riveted or otherwise rigidly secured to the outside of the roof.

15 The object of the invention is a strong roof having but few parts.

A further object is a roof which can be constructed off the car and put on as a whole.

Further objects of the invention appear in 20 connection with the following description of the embodiment thereof which is illustrated in the accompanying drawings.

In the drawings, in which the same reference characters are used to designate like 25 parts in the several views, Figure 1 is a vertical cross-section and perspective view of the end portion of a car roof embodying my invention, the running boards being broken away in part to disclose one of the 30 running board saddles; Fig. 2 is a vertical section through a seam and carline at the ridge, on the line 2—2 in Fig. 1; Fig. 3 is a fragmentary view of the eaves of the roof, showing the end of a carline; Fig. 4 is a 35 vertical cross-section at the eaves on the line 4—4 in Fig. 3; Fig. 5 is a vertical section through a seam and carline taken transversely thereof, showing a welded joint; and Fig. 6 is a view similar to Fig. 4, showing a 40 modification of the eaves construction.

In the drawings, the roof is shown applied to a car having metal siding 11 and Z bar side plates 12, but the roof can be applied to other kinds of cars having either 45 metal or wood side plates.

In the construction illustrated in Figs. 1 to 4, the roof plates 13 are arranged cross-wise of the car, extending from eaves to eaves in arcs of circles. The side margins 50 of the roof plates are turned up at right angles, forming side flanges 14 extending from end to end of the roof plates. The flanges 14 are of the same height from one end of the flange to the other. The ends of 55 the roof plates overhang the side plates of the car, and are riveted to angle strips 15

which extend lengthwise of the car outside of the side plates and below the eaves ends of the roof plates. These angle strips may be carried around the ends of the car, or 60 the outer margins of the two end roof plates may be bent down over the ends of the car and fastened thereto. The roof plates are arranged side by side with the adjacent flanges 14 of successive roof plates in contact. Pressed sheet metal seam covers 16 of inverted U shape in cross-section are fitted over the pairs of contacting flanges 14, and the seam covers and flanges are fastened together by rivets passing completely through 70 them. The seam covers are higher at the ridge than at the eaves, and the height diminishes gradually from the ridge to the eaves, in order to provide sufficient vertical stiffness to support the weight of the roof 75 with a minimum height at the eaves. Thus the seam covers also constitute outside carlines for the roof. The seam covers or carlines have marginal flanges 17 along their bases, which flanges bear upon the roof 80 plates alongside of the seams and stiffen the roof in addition to increasing the tightness of the seams. The running boards 18 are supported on pressed steel running board saddles 19, which have horizontal 85 marginal portions 20, to which the running boards are bolted, and middle saddle portions which straddle the seam caps and rest on their tops. The running board saddles have lugs or ears 21 struck down on 90 each side of the saddle portions to embrace the sides of the seam covers, and horizontal bolts or rivets through these lugs and the seam covers secure the running board saddles in place. 95

The roof may be riveted over a suitable form and then dropped in place on the car, with the vertical flanges of the eaves angle strips 15 against the outside of the side plates, to which they may be riveted or 100 otherwise securely fastened. This method of application insures that the roof plates and seam covers shall be properly assembled for riveting.

This invention enables a car to be 105 equipped with a rigid riveted roof free from initial strains produced in the operation of putting it on the car, and free from vertical rivet holes through which water might find its way into the car.

Figs. 5 and 6 illustrate modifications in 110 the construction of the joints between the

roof plates and at the eaves, respectively. The seam shown in Fig. 5 is spot welded; that is, welded together in spots 22 only, by means of clamping electrodes. Either electric welding apparatus, oxy-acetylene welding apparatus, or other suitable means may be used for welding the seams. In the construction shown in Fig. 6, the ends of the roof plates are bent down against the side plates, forming end flanges 23, which may be welded or otherwise secured directly to the side plates. An angle eaves strip is not required in the construction shown in Fig. 6, but may be used, if desired, to stiffen the roof along the eaves.

The invention is not restricted to the particular forms and arrangements of parts shown and described.

I claim the following as my invention:

1. A car roof comprising metal roof plates extending from eaves to eaves and having upstanding flanges along their side margins, said flanges being of substantially uniform height from end to end, and cover strips of inverted U shape arranged over the adjacent flanges of said roof plates, said cover strips having a greater height at the ridge than at the eaves of the roof, and means for securing said flanges and cover strips together to form a rigid joint, whereby said flanges and cover strips together constitute transverse supporting members.

2. A car roof comprising metal roof plates extending from eaves to eaves and having upstanding flanges along their side margins, said flanges being of substantially uniform height from end to end, and cover strips of inverted U shape with outwardly projecting flanges along the bottom edges of the side walls arranged over the adjacent flanges of said roof plates, said cover strips having a greater height at the ridge than at the eaves of the roof, and means for securing said flanges and cover strips together to form a rigid joint, whereby said flanges and cover strips together constitute transverse supporting members.

3. A car roof comprising metal roof plates extending from eaves to eaves and having upstanding flanges along their side margins, said flanges being of substantially uniform

height from end to end, cover strips of inverted U shape arranged over the adjacent flanges of said roof plates, said cover strips having a greater height at the ridge than at the eaves of the roof, means for securing said flanges and cover strips together to form a rigid joint, and continuous eaves strips arranged lengthwise of said roof under the eaves ends of said roof plates and rigidly secured thereto, whereby said flanges and cover strips together constitute transverse supporting members.

4. In a car roof, in combination, metal roof plates extending from eaves to eaves and having upstanding flanges along their side margins, the flanges of adjacent plates being rigidly fastened together along lines parallel with and close to the bottoms of the flanges, cover strips of inverted U-shape arranged over said flanges and secured thereto along the same lines that said flanges are fastened together on, said cover strips having a greater height than the height of said flanges at the ridge, and running board saddles embracing and rigidly secured to the tops of said flanges at the ridge and stiffening them against buckling.

5. A car roof constructed so as to be adapted to be handled as a separate unitary structure, said roof consisting of plates having upturned side flanges arranged side by side and rigidly secured together, stiffening means for the upstanding joints formed by said flanges, and stiffening means for the eaves ends of the plates.

6. A car roof constructed so as to be adapted to be handled as a separate unitary structure, said roof consisting of plates having upturned side flanges arranged side by side and rigidly secured together, stiffening means for the upstanding joints formed by said flanges, and stiffening means for the eaves ends of the plates, said eaves stiffening means being continuous and extending along the whole length of the roof.

Signed at St. Louis, Mo., this 22nd day of June, 1914.

WALTER P. MURPHY.
